UNITED STATES PATENT OFFICE.

MATTHIAS RALPH, SR., OF URSA, ILLINOIS.

CAR-COUPING.

SPECIFICATION forming part of Letters Patent No. 284,896, dated September 11, 1883.

Application filed June 8, 1883. (No model.)

To all whom it may concern:

Be it known that I, MATTHIAS RALPH, Sr., of Ursa, in the county of Adams and State of Illinois, have invented a new and useful Improvement in Car-Couplings, of which the following is a full, clear, and exact description.

Reference is to be had to the accompanying drawings, forming part of this specification, in which similar letters of reference indicate corresponding parts in all the figures.

Figure 1 is a side elevation, partly in section, of my improvement shown as applied to the adjacent ends of two cars. Fig. 2 is a front elevation of the same shown as applied to the 15 end of a car.

The object of this invention is to facilitate the coupling and uncoupling of cars.

The invention relates to a car-coupling constructed with a lever connected at one end with 20 the coupling-pin by a chain, and provided at its other end with a hinged rod extending to the top of the car, so that the coupling-pin can be operated from the top of the car. To the upwardly-projecting rod is hinged the end 25 of an arm formed upon a rock-shaft which is provided with a forwardly-projecting arm, so that the coupling-pin can be operated from the top of an adjacent car, as will be hereinafter fully described.

30 A represents the draw-head, B the coupling-pin, and C the coupling-link, of a car-coupling.

To the head of the pin B is attached the lower end of a short chain, D, the upper end 35 of which is attached to the outer end of a le-

ver, E. The lever E is journaled at its middle part to and between brackets F, attached to the end of a car-body, G, and to its inner end is hinged the end of a rod, H, which passes up into such a position that it can be readily 40 reached and operated from the top of the car to raise and lower the pin B.

To the upper part of the rod H is hinged the end of an arm, I, formed upon or attached to a short shaft, J, which is journaled to the 45 projecting ends of bars K, attached to the top of the car-body G, or to a support attached to the said car-body.

To the shaft J is attached, or upon it is formed, an arm, L, which projects into such a 50 position that it can be reached and operated from the top of the adjacent car when the cars are run together. With this construction the brakeman, while standing in his place upon the top of the car, can raise the coupling-pin 55 B to couple and uncouple the cars.

Having thus described my invention, what I claim as new, and desire to secure by Letters Patent, is—

In a car-coupling, the combination, with the 60 rod H, connected with the pin B by the lever E and chain D, of the rock-shaft J and arms I L, substantially as herein shown and described, whereby the coupling-pin can be operated from the top of an adjacent car, as set forth.

MATTHIAS RALPH, SR.
